CLAIM

The ornamental design for the outside handle, as shown and described.

DESCRIPTION

FIG. 1 is a front elevational view of the outside handle showing my new design.

FIG. 2 is a top plan view thereof.

FIG. 3 is a bottom plan view thereof.

FIG. 4 is a right side elevational view thereof.

FIG. 5 is a rear elevational view thereof.

FIG. 6 is a front elevational view thereof with the handle lifted upward.

FIG. 7 is a right side elevational view thereof with the handle lifted upward.

FIG. 8 is a perspective view thereof; and,

FIG. 9 is a perspective view thereof with the handle turned to the left.

The broken lines are shown for illustrative purposes only and form no part of the claimed design.
